UNITED STATES PATENT OFFICE.

HERMAN TORJESEN, OF BROOKLYN, NEW YORK.

PARTITION.

Application filed May 27, 1921, Serial No. 473,013. Renewed February 23, 1924.

To all whom it may concern:

Be it known that I, HERMAN TORJESEN, a citizen of the United States, residing in the borough of Brooklyn, county of Kings, city and State of New York, have invented a certain new and useful Improvement in Partitions, of which the following is a specification, reference being had to the accompanying drawings, which form a part of the same.

The object of my invention is to provide a partition formed of rails, stiles and panels and built in units so that the said partition may be erected wherever desired, requiring very little, if any, cutting and fitting at the place of erection.

In the drawings,

Fig. 1 is an elevation view of my partition, partly broken away in places to show the construction thereof;

Fig. 2 is a cross-section taken along the line 2—2 of Fig. 1;

Fig. 3 is a perspective view of a stile or pilaster used in my partition;

Fig. 4 is an enlarged view of means for locking the partition in place;

Fig. 5 is a lever used for drawing up and locking the partition in place;

Fig. 6 shows the said lever in operative position;

Fig. 7 is a cross-section along the line 7—7 of Fig. 1, and

Fig. 8 is a cross-section along the line 8—8 of Fig. 1 looking in the direction of the arrow.

Referring now in detail to the drawings 9 represents a track secured to a floor along which it is desired to erect a partition; 10 represents pilaster stiles, one of which is intended to be positioned against a wall 11. Mounted on the track 9 are the baseboards 12 which baseboards are made of box construction provided with a moulding 13 and a groove 14 therein. The stiles 10 are also provided with a groove 14^a on each side thereof, and a groove 15 across the top thereof. The stile is also provided with openings 16 and 17 through the same and are provided with grooves 18 and 19 at the bottom thereof.

The baseboards 12 are formed of hollow construction provided with interior supports 20. The floor 21 forming the bottom of the groove 14 is extended beyond the ends of the baseboard section for the purpose of coupling the same with its respective

stile. Panels 22 are adapted to be fitted into the grooves 14 of the baseboards and 14^a of the stiles; 23 represents a rail of tubular form, having upper and lower 60 grooves 24 and 25 respectively therein. This rail is adapted to be fitted on the top of its respective partition 22, the upper end of the partition fitting in the lower end of the rail, and the upper groove is adapted 65 to carry the lower end of its respective upper partition 26. I provide a double moulding strip 27 for the top of my partition in which is embodied an extension strip 28 on which is contained a tongue 29, adapted to 70 fit in the groove 30 of the upper panel 26; 31 is a locking rod fastened by the securing element 32 in one of the stiles, and 33 is a lever bit used to draw up and lock the partition on the locking rod 31. 75

In operation a strip 9 is laid on the floor where it is desired to erect a partition of the form described over which one of the stiles 10 is erected and secured to a wall in any well known manner. A groove 34 is provided in the lower end of the stile for the purpose of straddling said strip 9. A section of the baseboards 12 is then straddled in place over the strip 9 and one of its extensions 21 is pressed into the recess 17 and 80 the ends of this baseboard pressed into the grooves 18 and 19 of the stile 10. It will be observed that the side of the stile and the top of the baseboard forming the right angle are provided with grooves which register 85 with each other. A panel 22 is then put in place in the grooves 14 of the baseboard and 14^a of the stile. The rail 23 is then straddled over the panel 22 which has just been put in place, the lower groove 25 in this rail accommodating the upper end of said panel. The right angle now formed by this rail and the upper part of the stile is provided with a continuous groove formed of the upper groove 24 of the rail and the said groove 14^a 90 of the stile. An upper panel 26 is then inserted in the groove 24 of the rail and 14^a of the stile. The locking rod 31 is then inserted in the tubular rail 23 and is secured in place in any convenient manner as by inserting a screw 35 or other holding element 95 through the stile 10 and into the locking rod 31. A second stile 10 is then strung onto the locking rod 31 and moved in place against the baseboard 12, the panel 22, the rail 23 100 and the upper panel 26, the groove 14^a of said second stile fitting over the said parti- 105 110

tion elements just referred to, the extension 21 of the baseboard fitting into the recess 17 of said second stile.

I have shown in the drawings a partition 5 of six panels in three tiers of two panels each, and have described the erection of one tier. The erection of the other tiers is accomplished by the same method as just described for the first tier. When the last stile 10 of the partition is in place the lever bit 33 is driven sufficiently into the locking rod 31 at an angle pointing toward the direction from which the partition has been built to hold its position in said rod, and a screw 35 15 is then inserted through the screw hole 36 and into the body of the last erected stile 10. As the screw is driven in, the lever bit gradually assumes an upright position drawing the elements of the partition just described 20 into tight relation with each other. Lever bits may of course also be used for the purposes stated at intermediate portions of the partition, as well as at the end. The moulding 27 is then put in place into the top 25 grooves of the stiles, the tongue 29 being inserted in the groove 30 of the upper panels.

I have described what I believe to be the best embodiment of my invention. I do not wish to be confined, however, to the embodiment shown and described but what I wish to cover by Letters Patent is set forth in the appended claims.

Claims:

1. In a partition stiles and panels, a tubular rail provided with upper and lower grooves to receive lower and upper edges of said panels respectively and a locking strip adapted to be passed through the said tubular rail and a lever bit, one end being adapt-

ed to be embedded in said locking strip, and 40 the other end adapted to be secured to a stile.

2. In a partition, a baseboard consisting of two faces, supports, said faces being separated from each other by said supports between the same, said baseboard containing a groove at its upper surface, adapted to receive the lower edge of a panel and extension elements at the ends of said baseboard adapted to fit said baseboard to adjacent 50 stiles.

3. In a partition, a plurality of stiles recessed at their upper and lower ends, baseboards having connecting elements adapted to be fitted into adjacent stiles, said baseboards and said stiles being provided with grooves, panels adapted to be fitted in said grooves, tubular rails provided with grooves at their upper and lower sides, mounted on said panels, the upper edge of said panels 60 and the lower groove of said rails cooperating with each other, upper panels fitted into the upper grooves of said rails and the adjacent grooves of said stiles, said upper panels being provided with grooves in their upper edges, and a moulding adapted to be fitted into the upper ends of said stiles and upper panels.

4. In a partition, a strip and means for securing the same in said partition, and 70 means cooperating with said strip for drawing up the elements of said partition, and locking the same together thereby, said means consisting of a lever bit, one end being adapted to be embedded in said strip, and the other end adapted to be secured to said partition.

HERMAN TORJESEN.
